(57) **CLAIM**

The ornamental design for a toy truck nightlight, as shown and described.

DESCRIPTION

FIG. 1 is a perspective view of a toy truck nightlight showing our new design;

FIG. 2 is a top plan view of the embodiment of FIG. 1;
FIG. 3 is a bottom plan view of the embodiment of FIG. 1;
FIG. 4 is a right side elevational view of the embodiment of FIG. 1;
FIG. 5 is a left side elevational view of the embodiment of FIG. 1;
FIG. 6 is a front elevational view of the embodiment of FIG. 1;
FIG. 7 is a rear elevational view of the embodiment of FIG. 1;
FIG. 8 is a perspective view of an alternate embodiment of the toy truck nightlight having reduced wheel, grille, and rear position lamp detail;
FIG. 9 is a top plan view of the embodiment of FIG. 8;
FIG. 10 is a bottom plan view of the embodiment of FIG. 8;
FIG. 11 is a right side elevational view of the embodiment of FIG. 8;
FIG. 12 is a left side elevational view of the embodiment of FIG. 8;
FIG. 13 is a front elevational view of the embodiment of FIG. 8;
FIG. 14 is a rear elevational view of the embodiment of FIG. 8;
FIG. 15 is a perspective view of an alternate embodiment of the toy truck nightlight having circular apertures and reduced wheel, grille, and rear position lamp detail;
FIG. 16 is a top plan view of the embodiment of FIG. 15;
FIG. 17 is a bottom plan view of the embodiment of FIG. 15;
FIG. 18 is a right side elevational view of the embodiment of FIG. 15;
FIG. 19 is a left side elevational view of the embodiment of FIG. 15;
FIG. 20 is a front elevational view of the embodiment of FIG. 15; and,
FIG. 21 is a rear elevational view of the embodiment of FIG. 15.
Surface shading is used to shade FIGS. 1-21 to show clearly the character and contour of all surfaces of the 3-dimensional aspects of the design and form a part of the design sought to be protected. Oblique line shading is used to show transparent or translucent surfaces.
